UNITED STATES PATENT OFFICE

CLARENCE W. CARTER, OF MINNEAPOLIS, MINNESOTA, ASSIGNOR, BY MESNE ASSIGNMENTS, TO HART-CARTER COMPANY, OF PEORIA, ILLINOIS, A CORPORATION OF DELAWARE

LIQUID-FLOW REGULATOR

Application filed July 30, 1925. Serial No. 47,148.

My invention provides an extremely simple and highly efficient liquid flow regulator, by the use of which a predetermined flow of liquid, per unit of time, may be very accurately maintained. Generally stated, the invention consists of the novel devices, combinations of devices and arrangement of parts hereinafter described and defined in the claims.

10 A liquid flow regulator of this character may be used to control the flow of various different liquids for various different uses, but the purpose may be best illustrated by noting one of its major uses, to wit: for supplying 15 to wheat the predetermined amount of water required to condition the same for milling; and in the further description of this regulator, it will be treated as designed for use for the particular purpose above just noted.

20 The invention is illustrated in the accompanying drawings, wherein like characters indicate like parts throughout the several views.

Referring to the drawings:

25 Fig. 1 is an elevation with some parts broken away and some parts sectioned, showing the complete regulator;

Fig. 2 is a plan view of the parts shown in Fig. 1, the cover being removed;

30 Fig. 3 is a vertical section on the line 3—3 of Fig. 2, some lower portions of the supporting standard being broken away;

Fig. 4 is a transverse section on the line 4—4 of Fig. 2; and

35 Fig. 5 is a diagrammatic view of the graduated flow-indicator scale shown as laid out flat.

The flow regulator may, of course, be supported and applied in various different ways, but, as shown, it is supported by a hollow pedestal 8, to the top of which is secured a cast plate 9. Mounted on the plate 9 is a liquid-container or tank 10 shown as constructed of sheet metal. This container 10 is provided with a water inlet and a water outlet. The water inlet 11 in the structure shown is formed through the sleeve-like portion of a valve casing 12 that extends through the bottom of the container and is connected thereto with a liquid-tight joint. A water

supply pipe 13, which is connected to a source of water supply under pressure, such as a city water pipe or an elevated tank, is connected to the water inlet 11. Mounted in the upper end of the inlet passage 11 is an upwardly opening valve 14 adapted to be opened by water pressure from the pipe 13 and to be closed by a float 15. This float 15 rides on the water contained in the container, and in the arrangement illustrated is connected by 60 a plurality of links 16 to levers 17 intermediate pivoted at 18 to the flange-like projection of the valve casing 12. The inner ends of the lever 17 engage on top of the inlet valve 14 and press the said valve closed when the 65 float 15 has been raised by the water in the container to a predetermined altitude. The float 15 and the connections described co-operate with the valve 14 to maintain within the container an elevation of water that somewhat approaches a constant altitude. This automatic regulation of the inflow of the water, however, is a minor feature, for, as will hereinafter appear, this improved flow regulator will operate with the greatest accuracy even with varying altitudes of the 70 water in the container.

The numeral 19 indicates an overflow pipe that is extended upward through the bottom of the container and the upper end of 80 which is slightly above the maximum altitude of the water maintained in the container by the action of the float 15. Said pipe simply prevents flooding if the float-actuated valve 14 should, for any reason, leak or fail to completely close. The numeral 20 indicates a 85 suitable cover for the container.

The water outlet of the container, as shown, is in the form of a tube or stack 21 that has a fluid-tight joint with the bottom 90 of the container and extends upward through the water therein contained to a point above the highest possible altitude of the water within the container, to wit: above the level of the upper end of the overflow pipe 19. 95 The water does not overflow directly through this outlet passage, but, as will presently appear, overflows directly through the floating weir and discharge pipe.

The salient features of this invention reside 100

in the provision of a floating weir for controlling the discharge of water from the container. This weir is carried by a float that rides on or in the water maintained in the 5 container, so that the weir, when set for any predetermined flow, will accurately maintain that flow, regardless of variations in the altitude of the water in the container. The most 10 approved form of this flow regulator is illustrated in the drawings and described in detail 15 is as follows:

The numeral 22 indicates an annular float that surrounds the outlet passage 21 with much clearance and carries an annular siphon 23, the inner end of which delivers into a bowl 24 that works freely within the discharge passage 21. The said float 22, annular siphon 23 and bowl 24 are connected and operate as a single unit and, of course, 20 are carried and supported by said float. The bowl 24 is provided with a depending internally threaded centrally located sleeve 25. Extended through the sleeve 25 and having threaded engagement therewith is a discharge tube shown as made up of two sections 25 26 and 27 connected together by sweating, friction or otherwise, so that they move together when rotated.

To complete the weir, the tube 27 is provided with a lateral discharge passage 28, which, as shown, extends somewhat below the upper edge of the tube 26, so that the upper edge of said tube 26 forms the lower line of said discharge passage. Preferably, the upper edge of said tube 26 is beveled so as to provide a sharp overflow edge for the discharged water. For a purpose that will presently appear, the discharge passage 18 is made of a peculiar form, to be hereinafter 40 more fully described.

To the upper end of the tube 27 is rigidly secured, by sweating or otherwise, a flanged head 29, and to this head a rotary cap 30 is attached by means of an axially located 45 screw 31. The cap 30 carries a depending annular indicator plate or scale flange 32 that is graduated, as best shown in Figs. 4 and 5, to indicate the setting of the weir for the flow of water in units of weight per 50 units of time. As shown, the said graduations indicate the setting of the weir for the flow of water in pounds per minute, and it will be noted that, in the arrangement shown, the graduations are in spiral arrangement, 55 so that the length of the scale is made several times the circumference of the annular indicator flange or plate 32. The graduations on this scale cooperate with a pointer or finger 33 located adjacent thereto and secured 60 on the top of the floating siphon 23. Also, it may be noted that the scale 33 is formed integral with the top plate that is clamped to the rotary cap 30 by one or more small screws 34, (see particularly Fig. 3). The cap 65 30 is capable of circumferential adjustments

in respect to the tube 27, so as to set the annular scale 32 correct in respect to the tube 27 and pointer 33.

In Fig. 3, the weir is shown as set for nearly maximum flow. By rotation of the cap 30 and discharge tube 26—27, the discharge passage 28 may be raised and lowered at will and the amount of flow for which the weir is set will be indicated on the scale 32. The spiral trend of the graduations on the scale 32 corresponds to the coarse threads on the sleeve 25 and on the discharge tube, so that the upper end of the pointer 33 will follow the spiral graduations on the scale 32 and indicate the exact setting of the weir. When the upper edge of the tube 26 is raised to or slightly above the level of the water in the bowl 24, the flow of water will be cut off. Of course, the level of the water in the bowl 24 will be the same as the level of the water in the container 10. In the machine illustrated, the discharge tube 26 is always free from but delivers into a basin or receptacle 35 secured to one side of the pedestal 8. This basin is provided with a discharge tube 36 to which a tube of any suitable kind may be attached for the delivery of the water to the grain or material to be dampeden.

In practice, I have found that, to provide graduations on the scale 32 that are of constant space progression in a circumferential direction, the cross section of the discharge passage 28, on different horizontal levels, must vary so as to give an irregular variation in the vertical outline of said discharge 100 passage. The outline shown in Fig. 3 is one which, in practice, I have found to accomplish the above result.

To start the flow regulator into action, the annular siphon 23 must, of course, be primed 105 or filled with water, and as a simple means for accomplishing this, I provide a small inverted priming siphon 37, the short leg of which terminates just below the top of the annular siphon, and the long leg of which extends through the top of the siphon and is rigidly attached thereto, as best shown in Fig. 3. When suction is applied to the projecting upper end of the priming siphon 37, air will be drawn out of the annular siphon 110 23, the said siphon 23 will be filled with water to its crown and all of that portion of the priming siphon 37 that is below the water level at the crown of the said siphon 23 will be filled with water so that said priming siphon then becomes a sealed water trap and the annular siphon 23 will be kept filled with water.

In a measuring instrument of the character above described, great accuracy is required, 125 and to provide for the greatest accuracy, it is necessary that the floating weir be free from side lash or pressure due to the flow of the water to and through the weir. This, I have found, may be very satisfactorily ac-

complished by the use of a baffle plate, such as best shown in Figs. 2, and 3, wherein the numeral 38 indicates a horizontal plate spaced from the bottom of the container 10 by brackets 39 and provided with a vertical flange 40 that extends between the floats 15 and 22 to a point above the maximum water level. The outer edges of the plate 38 and flange 40 are shown as spaced slightly from the walls of the container and, surrounding the annular outlet passage 21, said plate 38 is provided with a water passage 41 that is eccentric to said passage 21 and has its greatest distance therefrom at a point diametrically opposite to the float 15, so that the water will flow upward through said passage 41 with approximately equal velocity at all points surrounding said passage 21.

The siphon 23, as shown, is an endless siphon and such is a very desirable form, because it gives a centralized flow of the water, that is, a flow that is equally distributed from all points around and toward the axis of the floating weir.

25 When the liquid flow regulator is used, for example, to supply water to a flowing stream of grain, it is desirable that the flow regulator be cut out of action when the flow of grain is stopped or interrupted. A part only 30 of such device is illustrated in Figs. 1 and 3, wherein 50 indicates a spring motor such as used in thermostatically controlled furnace regulators, the rotor of said motor having a crank 52 connected by a link 54 to a lever 55 intermediately pivoted to a bracket 56 secured on the interior of the pedestal 8 and having its other end connected to the lower 35 end of a trip rod 57. The trip rod 57, as shown, works through the top plate 9 and to the upper end thereof is secured a forked head 58 that loosely embraces the sleeve 25 of the bowl 24. For the purposes of this case, it is only desirable to note that, when the motor crank 52 is in its normal upturned position, 40 the rod 57 and head 58 will be lowered and the floating weir will be in action, but when said crank 52 is turned downward, the rod 57 and head 58 will be raised, thereby lifting the floating structure 22—23—24 so that 45 the discharge passage 28 of the weir will be above the water level and the flow of water from the dam will be cut off. Any suitable means may be used for automatically actuating the motor 50, but since the tripping device constitutes no part of the present invention, its construction and operation need 50 not here be further traced.

From what has been said, it of course follows that the invention herein disclosed and 60 specifically illustrated in the drawings is capable of a large range of modification within the scope of the invention defined in the claims. The floating weir is herein considered to be a broadly new feature and is herein 65 generically claimed as applied in a device

for regulating the flow of liquids, irrespective of the character of the liquid and the material to which it is to be applied, if, in fact, the liquid is to be applied to any other substance. Several of these devices are capable of use, for example, to control the flow of several different liquids to be commingled in predetermined quantities or proportions.

What I claim is:

1. A liquid flow regulator comprising a liquid container and a floating weir controlling the flow of liquid from said container, and means for varying the flow controlled by said weir said parts being combined as a complete self-contained structure. 75

2. A liquid flow regulator comprising a liquid container and a floating weir controlling the flow of liquid from said container, said floating weir having a discharge passage that is vertically adjustable in respect to the water level to vary the flow controlled by said weir said parts being combined as a complete self-contained structure. 80

3. A liquid flow regulator comprising a liquid container having an inlet and an outlet, and a floating weir confined within said container and co-operating with the outlet thereof to control the flow of liquid from said container, said parts forming a self-contained complete liquid flow regulator. 90

4. A liquid flow regulator comprising a liquid container having an inlet and an outlet, a float within said container, and a weir carried by said float and controlling the flow of liquid from said container through said outlet, the said weir being vertically adjustable in respect to said float to vary the liquid flow said parts being combined as a complete self-contained structure. 100

5. A liquid flow regulator comprising a liquid container and a floating weir structure including a siphon, controlling the flow of liquid from said container. 105

6. A liquid flow regulator comprising a liquid container, and a floating weir structure controlling the flow of liquid from said container, said weir structure including a float, a bowl, and a siphon delivering liquid from said container into said bowl, and the component elements of said weir structure being connected for common floating movements. 110

7. A liquid flow regulator comprising a liquid container, and a floating weir structure controlling the flow of liquid from said container, said weir structure including a float, a bowl, and a siphon delivering liquid from said container into said bowl, said bowl having a discharge tube formed with a lateral water discharge passage opening from the bowl, and means for vertically adjusting said discharge tube in respect to said bowl, and the component elements of said weir structure being connected for common floating movements. 120

8. A liquid flow regulator comprising a liq-

uid container having an inlet and an outlet, the latter extending above a predetermined liquid level, a float within said container, a bowl carried by said float, a siphon carried by said float for maintaining a liquid level in said bowl similar to that in said container, and a weir controlling the flow of liquid from said bowl through said discharge passage.

10 9. A liquid flow regulator comprising a liquid container, a float within said container, a bowl carried by said float, a siphon carried by said float for maintaining a common level of liquid in said container and 15 bowl, and a weir connected to and vertically moved by said float and controlling the flow of liquid from said bowl.

10 10. A liquid flow regulator comprising a liquid container, a float within said container, 20 a bowl carried by said float, and a siphon structure connected to said bowl and float and centralized around the bowl so as to deliver a centralized flow of liquid from said container into said bowl, and a weir carried 25 by said bowl and controlling the discharge of liquid from said bowl.

11 11. A liquid flow regulator comprising a liquid container, an annular float within said container, a bowl axially located within said 30 float, a substantially annular siphon connecting said float and bowl and delivering from said container into said bowl, and a weir carried by said bowl and controlling the discharge of liquid from said bowl.

35 12. The structure defined in claim 11 in which said container has means for forming a discharge passage located between the radially inner and outer portions of said siphon and extended above the water level.

40 13. The structure defined in claim 8 in further combination with an inverted priming siphon applied to said first noted siphon, operating under suction to cause said first noted siphon to be filled with liquid and 45 then serving as a liquid-closed trap.

14. The structure defined in claim 8 in which said weir is in the form of a tube provided with a lateral liquid discharge passage and extends through the bottom of said bowl 50 and is vertically adjustable in respect to said bowl, and a scale indicating the vertical adjustment of said weir in respect to said bowl.

15. The structure defined in claim 11 in 55 which said weir is in the form of a tube projected through the bottom of said bowl and having threaded engagement therewith for vertical adjustments of the weir, said tube having a lateral liquid discharge passage.

60 16. The structure defined in claim 11 in which said weir is in the form of a tube projected through the bottom of said bowl and having threaded engagement therewith for vertical adjustments of the weir, said 65 tube having a lateral liquid discharge pas-

sage, a graduated annular scale applied to the upper end of said weir tube, and a cooperating relatively fixed pointer carried by the float structure.

17. A liquid flow regulator comprising a liquid container and an adjustable weir associated with and controlling the flow from said container, and an indicating element associated with said weir and having scale 70 graduations indicating the rate of flow, said indicating element being normally connected for movement by said weir, and means for adjusting said indicating element in respect to said weir to effect the proper setting thereof.

80 In testimony whereof I affix my signature.
CLARENCE W. CARTER.
